CELL TYPE FILTER

Earl G. Gunn, Racine, Wis.

Application January 25, 1951, Serial No. 207,740

2 Claims. (Cl. 210—169)

1

This invention relates to cell type filters and the form and arrangement of the filter elements of which the cell is constituted.

One form of cell type filter presently being produced involves a stack of disk-like elements of porous stock through which contaminated fluids, particularly oil, are drawn from the periphery of the stack to a central opening for the purpose of removing the contaminants. Various forms and relative arrangements of these elements have been employed, some providing for cross-flow, i. e., passing the fluid axially through the elements, or edge-wise flow, i. e., passing the fluid through the elements in the respective planes thereof.

The major problems in such an arrangement of elements are (1) obtaining an easy, rapid flow of a maximum quantity of fluid with a high degree of contaminant removal, (2) the economic formation and assembly of the elements into the finished cell, and (3) maintenance of the cell against easy shrinkage or other distortion during use so as to avoid decrease in its efficiency or too frequent replacement.

The main objects of this invention, therefore, are to provide an improved form of filter element and a relative radial angular arrangement of a plurality thereof in a stack for a cross-flow cell type filter; to provide an improved form of element whereby the laminated arrangement of a plurality thereof in a stack constitutes fluid pockets interposed between sector-shaped chambers opening at the periphery of the stack of elements and extending radially inward on both sides of the pocket and substantially coextensive with the area of the pocket, whereby the fluid is filtered transversely through an imperforate wall on both sides of a pocket and from which pocket the filtered fluid is drained into a central channel in the cell filter; to provide an improved form and arrangement of a series of superimposed elements such that a substantial portion of the peripheral area of the cell constitutes entrances to chambers overlying both sides of the pockets; to provide an improved form and arrangement of elements of this kind made of identical configuration; to provide an improved form and arrangement of elements which permits the respective elements to be peripherally sealed with an air-hardening viscous substance throughout the circumferential portions which define each pocket; and to provide an improved form and arrangement of filter elements of this kind which are economical to produce, which will permit the use of material of almost any desired porosity, and which will have great endurance under the severest use.

In the accompanying drawings:

Fig. 1 is a front view, partly elevation and partly section of a cell type filter constructed in accordance with this invention, as arranged in its housing;

Fig. 2 is an exploded view of a plurality of the individual filter elements all of one configuration

2

showing the relative angular arrangement for the formation of pockets and chambers; and

Fig. 3 is an enlarged sectional detail, showing the form of the pockets interposed between chambers and indicating the direction of flow of the fluid during the filtering process.

The distinctive concept of this invention involves a stack of superimposed filtering elements of identical disk-like form with imperforate and open sector-shaped sections so assembled that one element with an open section is interposed between alternate elements with imperforate sections to form a series of pockets intermediate sector-shaped chambers substantially coextensive with the area of each pocket, which chambers open at the periphery of the stack of elements to permit the fluid to enter the chambers and spread over on opposite sides of a pocket to filter through the imperforate sections into the pockets from which the filtrate is drained into an axial channel formed in the stack by registering openings in the hubs of the elements. Preferably the peripheral portions of the elements which coact to form the pockets are sealed with an air-hardening viscous substance so as to preclude entrance of fluid along that boundary of the pockets.

The herein shown embodiment of this invention comprises a plurality of disk-like elements of identical configuration 8, having sector-shaped imperforate and open sections so arranged that when the elements are superimposed in a stack 11 and angularly arranged they form several axial series of pockets 12 each pocket being closed along its circumferential periphery and interposed between chambers 13. The chambers 13, as will be noted later, are substantially coextensive with the pockets 12 and being open at the circumferential periphery of the stack 11 permit the fluid to be filtered to spread out in the chambers 13 and pass axially through substantially the entire area of the imperforate sections of the elements 8, 9, and 10 into the pockets 12. Such a stack 11 of angularly arranged elements is supported on a tube 14 for operative positioning in a housing 15 whereto the fluid for filtering is admitted and wherfrom the filtrate is discharged, as will be explained later.

The one-configuration filter element 8, a plurality of which constitute the stack 11 shown in Fig. 1, is formed with a sector-shaped section 16 and a pair of radial spokes 17. The sector-shaped section 16 is slightly more than a semi-circle with its chord 18 disposed on the opposite side of the diameter of the element from its circumference 19. This sector-shaped section 16 is formed with a sector-shaped opening 20 substantially equidistant from the sector-defining chord 18. This provides two sector-shaped imperforate portions 21 and 22 at opposite sides of the sector-shaped open portion 20. Between the two spokes 17, and between each spoke 17 and the adjacent imperforate portions 21 and 22 are spaces 23.

Within the hub portion 24 of each element 8 is formed a non-circular opening 25 communica-

cating through a slot 26 with the respective opening 20. As herein shown the opening 25 is in the form of a six-point star. This permits the elements, as they are formed or afterwards, to be assembled on a well-known type of indexing spindle whereby each element 8 will be disposed successively one-sixth of a circumference in advance of the previous one. To facilitate this assembling on an indexing spindle, and later to support bail rods 27 (see Fig. 1), apertures 28 are formed in the ends of the spokes 17 and around the peripheral edge of the sector-shaped section 16.

Thus, as will be apparent from Fig. 2 (reading upwardly), the successive angular disposing of these identical elements 8 results in a sector-shaped opening 20 in one element being located between the sector-shaped imperforate portions 22 and 21 of the next below and above elements, thereby forming the pockets 12. The spaces 23 between the spokes 17 and on each side thereof adjacent the sector-shaped imperforate portions 21 and 22 for the three elements 8 next above and below the ones that form a pocket 12 constitute the sector-shaped chambers 13 on the opposite sides of each pocket 12.

As will be most clear from Fig. 3 the chambers 13 extend from peripheral openings or inlets 29 radially inwardly to the superimposed hub portions 24 of these elements. These chambers 13 are practically coextensive with the entire area of a pocket 12. Therefore, the fluid entering the chambers 13 on both sides of a pocket 12—as indicated by the arrows 30—spreads over the entire area of the previous sections 21 and 22 and filters through these sections into the pocket 12 from whence the filtrate flows out through the slot 26 into the channel 21 formed by the registering hub openings 25. The openings or inlets 29 constitute nearly half of the peripheral area of the stack 11.

To block off the penetration of a fluid into the pockets 12 edgewise from the periphery of the stack 11 in between the adjacent abutting faces of the elements, a suitable seal 32 of some appropriate air-hardening adhesive substance is applied, as is indicated in Fig. 3.

So formed, a stack 11 of these angularly-arranged elements 8 is mounted on a tube 14 within the housing 15. The form and arrangement of the tube and housing is not critical to a cell type filter embodying this invention.

The tube 14 is of a diameter less than the shortest distance across the hub opening 25 so that with the stack 11 in place thereon the channel 31 extends axially the full length of the stack exteriorly of the tube 14. The channel 31 communicates with the interior of the tube 14 through an aperture 31a (see Fig. 1).

The stack 11 is interposed between end caps or plates 33 and 34. The latter sets on a fluid-seal gasket 35 resting on a hub plate 36 supported by an annular shoulder 37 on the tube 14. At the opposite end, a fluid-seal gasket 38 is interposed between the end cap 34 and a hub plate 39. At its lower end the tube 14 is formed with a collar 14a and is threaded internally for connection with a suitable conduit for conveying the filtrate to the point of use or storage.

The housing 15 is here shown of cylindrical form with a conical-shaped bottom and conical-shaped closure 40. Axially aligned openings in the base of the housing 15 and in the closure provide for the reception of the telescopically arranged tube 14 and bolt 41 whereby the tube 14, 75

with the filter stack 11 mounted thereon, is appropriately positioned in the housing 15, with the closure 40 drawn firmly down onto the housing 15. A spring 42 is interposed between the closure 40 and the hub plate 39 so as to yieldingly compress the elements 8 firmly against each other throughout the length of the stack. Fluid sealings gaskets 43 and 44 are interposed between the closure 40 and the upper rim of the housing 15 and between the head of the bolt 41 and the closure 40. The housing 15 is formed with a suitable fluid inlet 45 and a normally-plugged drain outlet 46.

Other variations and modifications in the details of the structure and arrangement of the parts may be resorted to within the spirit and coverage of the appended claims.

I claim:

1. A cell type filter comprising a stack of liquid-permeable elements of identical configuration, each element embodying a sector-shaped section of slightly more than semi-circular form supported on a hub section having a central opening and having a sector-shaped opening formed therein of less than one-third the area of the section and located circumferentially equidistant from the section chord so as to be disposed between two imperforate portions of the section of equal area, the sector-shaped opening of the section being tapered towards its inner end and communicating with a narrow slit extending from the inner end to the hub opening, and a pair of spokes radiating from the hub to form three equal area sector-shaped spaces the intermediate one of which is diametrically opposed to the sector-shaped section opening and the other two of which are diametrically opposed to the respective imperforate portions of the sector-shaped section, the elements being superimposed in the stack with the central hub opening registering axially of the stack and so angularly arranged that the sector-shaped opening of the sector-shaped section of one element is interposed between the imperforate portions of the sector-shaped sections of two other elements thereby constituting a pocket between such imperforate portions disposed in axial registration with the spaces between the spokes of each two elements above and below, and whereby the spokes define peripherally-open chambers on opposite sides of each pocket for the reception of fluid to be filtered through the imperforate portions of the sector-shaped sections into the pocket for draining into the central hub opening.

2. The structure of claim 1 wherein the peripheral edges of the three sector-shaped sections which constitute a pocket are sealed with an air-hardening substance against the entrance of a fluid into the pocket between the abutting faces of the section.
